UNITED STATES PATENT OFFICE

ARTHUR W. HAHN, JR., OF BRONX, NEW YORK

SOAPING DEVICE

Application filed December 31, 1927. Serial No. 243,946.

My invention relates to soaping devices and refers particularly to soaping devices adapted to deliver a flow of either fresh water or soap solution as desired.

The object of my invention is a device capable of attachment to a water faucet whereby the movement of the delivering tube will cause the delivering of either fresh water or soap solution.

My device comprises a water chamber and a soap chamber and a delivering tube independent of both chambers and extending outwardly of the device at its delivering end, a movement of the delivering tube forming either an uninterrupted conduit from the water chamber for the delivery of fresh water externally of the device, or a connection between the water chamber and the soap chamber whereby the delivering tube will deliver water to the soap chamber, extract soap solution therefrom and deliver the soap solution through the delivering tube externally of the device.

The simplicity of construction, ease of operation and effectiveness of results of my device will be evident upon a consideration of my specification and its accompanying drawings.

In the accompanying drawings illustrating modifications of the device of my invention, similar parts are designated by similar numerals.

Figure 1 is a vertical section of one form of my device in fresh water delivering position.

Figure 2 is a fragmental view of Figure 1 in soap delivering position.

Figure 3 is a front view of one form of delivering device.

The particular form of the device of my invention shown in Figures 1, 2 and 3, comprises a water chamber having the cylindrical side 10 and the concave bottom 11, the lower portion of the side 10 being threaded. Extending inwardly from the top portion of the side 10 and supported by the knurled band 12 is a rubber nozzle 13, having the opening 14 capable of placement over a faucet (not shown).

A dependent soap chamber has the cylin-

drical side 15 extending into the bottom member 16, and carrying the knurled band 17. The upper portion of the side 15 has the shoulder 18 and is threaded to mesh with the threads of the water chamber. A gasket 19 forms a water tight joint between the water chamber and the soap chamber.

The water chamber bottom 11 has a central opening, the periphery of which is extended downwardly into the cylindrical bushing, or split sleeve 20 having an extended annular flange 21 capable of fitment with the extended annular flange 28 of the tube 23, thus holding the tube 23 in its upward position.

The soap chamber bottom 16 has an opening in alignment with the water chamber bottom opening and carries the rubber bushing 22.

Slidable within the openings of the water chamber bottom and the soap chamber bottom is a tube 23, open at both ends, having opposed openings, as 24, in the upper portion, carrying the flange stop member 25 and 26.

The lower end of the tube 23 carries a plurality of rings 29, 29 capable of retaining the rubber hose 30, the free end of which carries the removable nozzle 31 having the slit opening 32. Various nozzles may be used for specific purposes.

The operation of the device is as follows:

A water faucet is inserted within the opening 14 of the rubber nozzle 13. When the device is in the position shown in Figure 1, the openings 24, 24 of the tube 23 are closed by the sleeve 20 and, hence, the water will flow directly from the water chamber through the tubes 23 and 30 thus supplying fresh water. When the tube is drawn downwardly into the position shown in Figure 2, the openings 24, 24 of the tube 23 will connect the tube with the soap chamber and the water will pass through the water chamber, the upper portion of the tube 23 and through the openings 24, 24, into the soap chamber containing soap particles, and will thus form a soap solution which will pass through the openings 24, 24 into the tube 23 and outwardly through the tube 30 thus furnishing soap solution.

It will thus be seen that either fresh water

or soap solution can be obtained by the vertical movement of the tube 23.

In the modification shown in Figure 4, the rubber nozzle 13 is connected to the sleeve 33 by means of the band 34, the nozzle 13 thus forming the water chamber.

It will thus be seen that my device comprises a water chamber and a soap chamber separated by an imperforate wall, the delivering of fresh water or soap solution being controlled and determined by the movement of a tube passing from the water chamber through the soap chamber.

It will be noted that when the tube connects the water chamber with the soap chamber, the same openings in the tube deliver water into the soap chamber and extract soap solution therefrom.

My device, therefore, presents an inexpensive and effective means whereby fresh water and soap solution may be readily obtained from a fresh water supply.

I do not limit myself to the particular size, shape, number and arrangement of parts as shown and described as these are given simply as a means for clearly describing the device of my invention.

What I claim is:—

1. In a soaping device, in combination, a lower casing forming an interior soap chamber, an upper casing fixedly attached to said lower casing forming a water chamber having an opening into said soap chamber, said two casings being non-revoluble with respect to each other, a downwardly extended wall within said upper casing capable of attachment to a water supply faucet, a vertically movable delivering tube extending from the water chamber through the soap chamber and thence outwardly through the bottom of said lower casing and means whereby a vertical movement imparted to said tube externally of the lower casing will selectively allow the delivering of fresh water or soapy water through said delivering tube externally of said lower casing.

2. In a soaping device, in combination, a lower casing forming an interior soap chamber, an upper casing fixedly attached to said lower casing forming a water chamber having an opening into said soap chamber, said two casings being non-revoluble with respect to each other, a downwardly extended wall within said upper casing capable of attachment to a water supply faucet, a vertically movable delivering tube extending from the water chamber through the soap chamber and thence outwardly through the bottom of said lower casing and having a plurality of openings therein, means whereby a vertical movement imparted to said tube externally of the lower casing will selectively connect said water chamber with said soap chamber through said openings allowing the delivery of soap solution through said tube externally of the

lower casing and will close said openings allowing the delivery of fresh water through said tube externally of the lower casing.

3. In a soaping device, in combination, a lower casing forming an interior soap chamber, an upper casing fixedly attached to said lower casing forming a water chamber having an opening into said soap chamber, said two casings being non-revoluble with respect to each other, a downwardly extended wall within said upper casing capable of attachment to a water supply faucet, a vertically movable delivering tube extending from the water chamber through the soap chamber and thence outwardly through the bottom of said lower casing and having a plurality of openings therein, means whereby a vertical movement imparted to said tube externally of the lower casing will selectively connect said water chamber with said soap chamber through said openings allowing the delivery of soap solution through said tube externally of the lower casing and will close said openings allowing the delivery of fresh water through said tube externally of the lower casing and means for limiting the vertical movements of said tube.

Signed at New York City, in the county of New York and State of New York, this 27th day of December, 1927.
